UNITED STATES PATENT OFFICE.

JAMES H. FOOTE, OF CINCINNATI, OHIO.

WINDOW-SASH.

SPECIFICATION forming part of Letters Patent No. 426,791, dated April 29, 1890.

Application filed June 25, 1889. Serial No. 315,496. (No model.)

To all whom it may concern:

Be it known that I, JAMES H. FOOTE, a citizen of the United States, residing at Cincinnati, in the county of Hamilton and State of Ohio, have invented certain new and useful Improvements in Window-Sashes; and I do hereby declare the following to be a full, clear, and exact description of the invention, such as will enable others skilled in the art to which it appertains to make and use the same.

The first part of my improvements consists in attaching a spring or yielding guide to each side of a window-sash, which guides 15 traverse vertical grooves in the frame or casing, and thereby exclude rain, dust, &c., and prevent rattling, as hereinafter more fully described.

The second part of my improvements consists in a special construction of these spring-guides, whereby they are adapted for use 20 with box-windows containing the usual sash-weights, as hereinafter more fully described.

The third part of my improvements comprises a novel combination of devices for attaching the spring-guides to the window-sash, as hereinafter more fully described.

The fourth part of my improvement consists in such a construction of the sash-cord 30 fastener as will enable it to assist the yielding action of the spring-guide, as hereinafter more fully described.

In the annexed drawings, Figure 1 is an enlarged perspective view of one of my spring-guides detached from a sash. Fig. 2 is a vertical section of a portion of a window-frame with a spring-guide attached to a sash and a sash-cord applied to said guide. Fig. 3 is an enlarged horizontal section through said 35 frame and sash. Fig. 4 is an enlarged sectional elevation of a portion of a guide and the sash-cord fastener. Fig. 5 is an enlarged horizontal section thereof. Figs. 6, 7, and 8 show three different modifications of my invention.

Referring to Figs. 2 and 3, A represents a portion of an ordinary box-window frame or casing, and α is a vertical groove in the same, which groove is traversed by the sides or 40 spring portions B B' of a plate C, which members B B' C constitute the spring-guides previously referred to.

It is preferred to make the plate C somewhat longer than the sides B B', as seen at D D' in Fig. 1, and to perforate these extensions 55 at $d d'$, respectively. Furthermore, it is preferred to provide these members B B' C with inwardly-projecting shoulders or stops E, of any suitable shape, that will serve as a bearing for the sash-cord fastener F to pull against. 60 This fastener has one end of a sash cord or chain G attached to it, which support G passes over a pulley and has a suitable weight secured to its other end.

H is a window-sash, to which the guide is 65 secured by screws I, passing through the perforations $d d'$ of the extensions D D', and in some cases these extensions may be strengthened by clip-plates, one of which is seen at J.

K is a vertical groove in the edge of the 70 sash, into which groove a portion of the spring-guide is closely fitted, as seen in Fig. 3. In fitting up a window with these attachments the extensions D D' are first properly bent to bear against the upper and lower edges of 75 the sash, as seen in Fig. 2, and are then secured in the manner shown. The cord G is then arranged so as to cause the fastener F to bear against the stops E, and thus support the sash at any desired elevation and in the 80 same manner as any ordinary sash. Consequently the sash can be raised and lowered with perfect ease, during which operation the spring sides B B' of the guide will yield and automatically adjust themselves to any irregularity or warping of the frame. Therefore these sides serve as self-acting or self-adjusting weather-strips, that effectually exclude rain and dust without adding very materially to the labor of raising and lowering 85 the sash. In addition to this advantage the close fit of the spring-guides prevents the sash rattling, no matter how hard the wind may blow. If preferred, the free edges of the sides B B' may be bent inwardly, as seen at 90 b in Fig. 3, to prevent the frame being cut, and similar bends may be made at the ends of said sides, as seen at b' in Fig. 4.

In Fig. 6 the stops E' E' have an inward and upward slope, while the sash-cord fastener F' is tapering, by which arrangement 100 said fastener tends to spread the sides B B', and thereby increase their spring action.

In the modification seen in Fig. 7 the frame-

groove is lined with a sheet-metal casing L, which diminishes friction and prevents any possible wear of said groove. This illustration also shows the sides of the guide bent inwardly at M to increase their elasticity, and said sides are pierced to admit a staple N, which secures the guide within the sash and serves as a means for attaching the suspending cord or chain. In the modification seen in Fig. 8 the inner side of the spring-guide is flush with the sash and is secured in place by a screw O, to which the cord or chain may be attached. Furthermore, this illustration shows a lock or other suitable fastener P for supporting the sash at any desired elevation, thus dispensing with cords and weights. It is evident these modifications include the leading feature of my invention—that is to say, they show a yielding or spring guide secured within a groove of the sliding sash and adapted to traverse a vertical groove of the frame or casing, and at the same time to serve as a self-adjusting weather-strip and an anti-rattling device. Finally, this spring-guide may be made of any suitable material, although sheet metal is preferred for obvious reasons.

I claim as my invention—

1. A sliding window-sash having a spring-guide secured thereto and traveling therewith, which guide consists of a center plate, as C, having outwardly-pressing wings, as B B', bearing against the opposite sides of a grooved frame, as a, substantially as described.

2. A sliding window-sash having a spring-guide secured thereto and traveling therewith,

which guide consists of a center plate, as C, having outwardly-pressing wings, as B B', bearing against the opposite sides of a grooved frame, as a, said spring-guide being furnished with stops for the sash-cord fastener to shoulder against, substantially as described.

3. A spring-guide for window-sashes, which guide is composed of a plate C, having yielding sides B B' and perforated extensions D d D' d', said sides and extensions being integral with said plate, as herein described.

4. The combination of sash H, groove K, spring-guide B B' C, perforated extensions D d D' d', clip-plate J, and fasteners I, as herein described.

5. The spring-guide B B' C, having inwardly and upwardly sloping stops E' E', in combination with the tapering cord-fastener F', for the purpose described.

6. The combination of grooved frame A a, grooved sash H K, spring-guide B B' C, stops E, fastener F, and sash-cord G, for the purpose described.

7. The combination of a vertically-grooved window-frame, a vertically-grooved window-sash, and a spring-guide, which guide is secured within the sash-groove, has outwardly-pressing wings that traverse the frame-groove, and serves as the only means for confining said sash to said frame, substantially as described.

In testimony whereof I affix my signature in presence of two witnesses.

JAMES H. FOOTE.
